C. E. RENFROE

PORTABLE ROTARY BARBECUE MACHINE

Filed July 26, 1926

Inventor
Clarence E. Renfroe

Attorney
Thomas S. Wiley Jr.

UNITED STATES PATENT OFFICE.

CLARENCE E. RENFROE, OF PORTLAND, OREGON.

PORTABLE ROTARY BARBECUE MACHINE.

Application filed July 26, 1926. Serial No. 125,010.

My invention relates to barbecuing machines of the portable type, and has for its object, the barbecuing of meat before an open fire. The machine primarily consists of a frame structure, lined with fire brick, and having a vertically disposed griddle disposed within the same adapted to the maintaining of a live fire therebehind. An adjustable driving mechanism is disposed on the front of the device, adapted to rotate the spindles, carrying the spits for maintaining the products to be roasted thereupon, which said spindles and spits are adaptable to a frame for moving to and away from the fire; means being also provided for the removing of either of the spindles independent of the other, without interfering with the rotation of the remaining spindle.

A further object of my invention consists in providing portable mechanism having a power unit disposed thereupon, as an electric motor, which may be moved from place to place, as a completely assembled mechanism.

A further object of my invention consists in placing a hood and stack above the same to carry off the products of combustion and roasting.

A further object of my invention consists in placing a drip pan and ash scuttle immediately below and in the base of the device.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the accompanying drawing, forming a part of this application, in which like reference characters refer to like parts:

Figure 1 is a front elevation of my device.

Fig. 2 is an end elevation showing the manner of securing the slidable frame constituting my invention to the furnace bottom.

Fig. 3 is a cross section of Fig. 1, taken on line 3—3 thereof.

Fig. 4 is a perspective view of the sliding frame that supports the operating mechanism and the spits.

Fig. 5 is a detailed view of one of the spits and its associated gear.

In my invention 1 represents the outer jacket of the furnace, which has a hood 2 projecting outwardly over the open front thereof. 3 is a flue leading through the top of the furnace and provides a means for the escape of the gases from the hood and the furnace proper. The furnace is lined on the interior with a fire resistant material, which may be the fire brick 4, or it may be lined with other fire resistant material which may be placed therein in a plastic state. A horizontal grate 5 is disposed transversely of the furnace and spaced apart from the bottom thereof.

A vertical open faced grid 6 is mounted within the furnace parallel to the rear wall thereof. A space is provided between the grid and the rear wall to receive fuel, which may be charcoal, or coal; and, if desired, a proper burner may be placed therein to burn liquid fuel, such as gas. An ash-pan 7, is placed within the space beneath the grate 5, and may be removed through an opening in the front of the furnace.

Extending from the grate 5 outwardly, is a shelf 8, which is supported at its outer edge by the bracket 9. A drip-pan 10, may be placed upon the shelf 8, into which fatty products and the juices of the roasts may drip.

In a device of this kind, it is desirable to move the articles to be roasted to or from the fire, and I accomplish this by providing a slide frame composed of the side members 11 and 11^A which are secured together in parallel alignment by the cross bar 12, as illustrated in Fig. 4. The rivets 13 show one method of securing the side members to the cross bar. A slot 14 is formed in the side members 11 and 11^A which fit about and slide upon the roller supports 15, which are secured to the side walls of the furnace. This permits the side members to be moved to and from the fire in the furnace. To maintain said side members in an upright position, the rollers 15^A are provided to engage the lower edge thereof.

The side member 11 has a base 17, extending downwardly and outwardly therefrom. This base is provided to support an electric motor 16, or other prime mover. In this instance an electric motor is shown.

A reduction gear 21 is mounted on the

outwardly extending base 22 at the side of the side member 11. The reduction gear shown is preferably of the worm and gear type; but any desired type, within the limits 5 of construction herein shown, may be used.

The high speed shaft 20 of the reduction gear has a pulley 18 mounted thereon, which is connected to the pulley of the motor 16 by a chain drive, or as herein shown by a belt 10 19. The low speed shaft 27 of the reduction gear 21, extends through the hole 27^A of the side member 11, and has a chain sprocket 28 mounted upon the outer end thereof.

A stub shaft 31 extends through the hole 15 27^B of the side member 11, and is maintained therein by suitable bearings. Sprocket 30 is mounted on shaft 31 and in alignment with sprocket 28, mounted on shaft 27. Gear 32 is mounted at the outer end of stub shaft 20 31. Sprockets 28 and 30 are connected by the chain drive 29.

Vertical slots 36 are formed in the upper ends of side members 11 and 11^A, and oblique slots are formed in the outer edges thereof, 25 which are provided to receive the spindles 23 and 24. The spindles 23 and 24 have each one pointed end and one blunt end. A circumferential groove 37 is formed in each of the spindles adjacent the blunt end; and 30 when the spindles are placed within the slots 35 and 36, the circumferential grooves engage the slots and prohibit any lateral movement of the spindles. Gears 33 and 34 are mounted on the spindles 24 and 23 respectively, and engage and are to be rotated by gear 32 on the stub shaft 31. To maintain the articles to be barbecued in a proper position upon the spindles, detachable hooks 35 25 and 26 are provided.

40 The operation of my device is as follows: The prime mover through the medium of the reduction gear 21, rotates the sprocket 28 which in turn is connected to and rotates the sprocket 30 on the stub shaft 31, and 45 the gear 32 also on said stub shaft. The spits or spindles 23 and 24, are rotated through the gears 33 and 34 engaging gear 32 of the stub shaft.

Heretofore in a device of this character, 50 the spits have been mounted on an immovable frame work before the fire, which necessitated the removal of the spits when the fire became too hot. Applicant has overcome this difficulty by providing a slidable frame 55 work which may be moved toward or from the fire, while the device is in operation. Applicant has also provided means whereby either of the spits may be operated independently of the other, and either spit may be 60 removed without stopping the operation of the other.

While the form of mechanism herein shown and described is admirably adapted to fulfill the objects primarily stated, it is to 65 be understood that it is not intended to con-

fine the invention to the one form of embodiment herein shown and described, as it is susceptible of embodiment in various forms, all coming within the scope of the claims which follow:

What I claim is:

1. In a portable rotary barbecue, a fire proof open front furnace, a vertical grid disposed parallel the rear wall of said furnace and spaced apart therefrom, a horizontal grate parallel the bottom of said furnace and spaced apart therefrom, a horizontal shelf extending outwardly from said grate, outstanding rollers disposed at each side of said furnace, parallel side members slidably 70 on said rollers, a prime mover and a train of gears mounted on one of said side members, detachable spits rotatably supported by said side members, and gears mounted on said spits to engage with and be rotated by 75 said train of gears.

2. In a portable rotary barbecue, an open front furnace having a fire proof lining, a hood disposed outwardly at the top of said furnace, a flue disposed at the top of said furnace and leading thereinto, a horizontal grate within said furnace and spaced apart from the bottom, a vertical grid mounted within said furnace and spaced apart from the rear wall thereof, a horizontal shelf extending outwardly from said grate, horizontal rollers mounted to each side of said furnace, side members slidably mounted on said rollers, a cross bar securing said side members in parallel alignment, a prime mover and a train of gears mounted on one side of said side members, a stub shaft rotatably mounted on said last mentioned side member, and rotatably connected to said train of 80 gears, a gear mounted on said stub shaft and rotating therewith, there being a plurality of slots formed in said side members, removable spindles rotatably maintained in said slots, and gears mounted on said spindles, and engaging with and rotated by the gear 85 mounted on said stub shaft.

3. In a portable rotary barbecue, the combination of a furnace having a fire proof lining, a hood disposed outwardly at the top of said furnace, a flue disposed at the top of said furnace and leading thereinto, a vertical grid mounted within said furnace and spaced apart from the rear wall thereof, a horizontal grate mounted within said furnace and spaced apart from the bottom thereof, a removable ash-pan disposed below said grate, a horizontal shelf extending outwardly from said grate, outstanding rollers disposed at each side of the furnace, side members slidably mounted on said rollers, a cross bar securing said side members in parallel alignment, a reduction gear mounted on one of said side members and having a low speed shaft extending therethrough, an electric motor mounted on said side member, a belt 100 105 110 115 120 125 130 135

connection, a pulley mounted on said electric motor with a pulley mounted on the high speed shaft of the reduction gear, a chain sprocket mounted on the low speed shaft of the reduction gear, a stub shaft rotatably mounted through said last mentioned side member, a chain sprocket mounted on said stub shaft and connected by a chain drive to the chain sprocket mounted on the low speed shaft of the reduction gear, a gear mounted on said stub shaft, there being a plurality of slots formed in said side members, a plurality of spindles each having one pointed and one sharp end, removably maintained within said slots, there being a ¹⁵ circumferential groove formed in each of said spindles and engaging with the gear mounted on the stub shaft, and detachable hooks mounted upon said spindle.

CLARENCE E. RENFROE.
